ADJUSTABLE ERASER DEVICE

Charles A. Watrous, Des Moines, Iowa

Application July 28, 1933, Serial No. 682,605

4 Claims. (Cl. 120—36)

Pencils with adjustable and replaceable leads are now in common use, but are customarily provided with erasers which are not adjustable and are relatively short and exposed beyond the end of the pencil and soon become soiled, to such extent as to render them inefficient for pencil erasing purposes, and they are necessarily relatively short and soon become worn out.

The objects of my invention are to provide an eraser attachment for pencils of simple, durable and inexpensive construction, and in which a relatively long eraser may be used, and which when not in use is contained within the lead pencil and which may be readily and easily projected to any desired length beyond the end of the pencil by the same kind of movement now employed in projecting and withdrawing leads from the pencil.

A further object is to provide a pencil of this character in which the screw for longitudinally adjusting the eraser is projected through a central opening in the eraser, so that the eraser and screw occupy the same space within the pencil, and whereby when the eraser is projected beyond the end of the pencil, the screw will assist in bracing and stiffening the eraser.

A further object is to provide improved means for detachably and replaceably connecting an eraser with the adjusting nut co-operating with the adjusting screw, and whereby the parts may be firmly and detachably held together and at the same time freely rotated for advancing or retracting the eraser.

My invention consists in the construction, arrangement and combination of the various parts of the device, whereby the objects contemplated are attained, as hereinafter more fully set forth, pointed out in my claims, and illustrated in the accompanying drawing, in which:

0. Figure 1 shows a vertical, central sectional view of a part of a pencil having my improved eraser connected therewith, taken on the line 1—1 of Figure 5.

5. Figure 2 shows an enlarged detail view of the screw and adjusting nut and adjacent parts, taken on the line 2—2 of Figure 3.

Figure 3 shows an end elevation looking at the eraser.

0. Figure 4 shows an isometric view illustrating the eraser and its socket.

Figure 5 shows a side elevation of a complete pencil having my eraser attachment applied thereto.

5. Figure 6 shows an isometric view illustrating

the screw supporting block and the detachable screw threaded collar adjacent thereto.

Figure 7 shows a detail longitudinal sectional view of a modified form of eraser socket connected to the adjusting nut; and

Figure 8 shows an isometric view of the adjusting nut and sleeve.

Referring to the accompanying drawing, I have used the reference numeral 10 to indicate the pencil portion of the device, and 11 a tubular body 10 rotatively connected with the pencil portion. This tubular body has the usual holder 12 fixed to it. Fixed to one end of the body 11 is a screw supporting block 13 projected above the body 11 and having fixed therein a screw 14. The upper portion of the screw supporting block 13 is reduced in diameter and a ring 15 is rotatively mounted thereon and detachably held in place by a screw threaded collar 16.

The reference numeral 17 indicates generally the eraser holder which is fitted down over the screw supporting block 13 and which is fixed by solder or otherwise to the ring 15. This eraser holder is open at its upper end.

Mounted upon the adjusting screw 14 is the 25 adjusting nut 18 having a screw threaded opening through which the adjusting screw is projected. This nut has a sleeve 19 fixed to it and projected above it and having its upper end turned slightly at 20.

The eraser is indicated generally by the reference numeral 21 and is of a length substantially as great as that of the adjusting screw, and is preferably on two opposite sides provided with flat faces, and has a longitudinal central opening 22 extending through it from one end to the other. Fixed to its lower end is a sleeve 23, having a depression near its central portion, as clearly shown at 24 in Figure 2.

This eraser and its sleeve are inserted in the holder with the screw projecting through the opening 22 and the sleeve 23 is forced down into the sleeve 19 until the inturned edges 20 thereof enter the notches 24 in the sleeve 23, thereby securely holding the eraser against movement away from the adjusting nut, and yet permitting its removal for replacement purposes.

In the modified form shown in Figure 7 I have shown the sleeve 25 connected to the nut 18, and having inwardly extended projections 26 to 50 enter the eraser 21 and detachably but firmly holding the eraser to the nut 18.

In practical use I have demonstrated that when the eraser is in its withdrawn position, as shown in Figure 1, it will be protected against being 55

soiled by handling and use, because it is withdrawn within the pencil casing. When it is desired to use the eraser, the operator holds the eraser holder in one hand and the pencil body 11 5 in the other hand and rotates one relative to the other, to thereby project the eraser beyond the end of the eraser holder in substantially the same manner as the leads are projected with the customary adjustable lead pencils.

10 When the eraser has been projected the desired distance beyond the eraser holder, I have found that the rigid screw 14 within the interior of the eraser serves to substantially brace and support the eraser, and hence a very flexible eraser may 15 be employed.

It is well known in the art that at the present time the kind of erasers that are now customarily used, and which are placed in a sleeve connected with the lead pencil or other holder, are necessarily made relatively stiff in order that they may 20 be mechanically held within the sleeve when subjected to heavy pressures when used for erasing purposes, because if the eraser were made relatively soft and flexible, it would, when subjected to such use, be drawn out of the tubular holder. It is also well known in the art that for maximum efficiency for erasing purposes, it is desirable that the eraser be made much softer and more flexible than the ones now in common use.

30 I have demonstrated in practice with my improvement that I have successfully employed a relatively soft flexible eraser and entirely obviate the objection of having the eraser accidentally withdrawn from its supporting sleeve when heavy pressures are used upon it for erasing purposes. In practice with my improvement, and with a relatively soft eraser, the reinforcing member extended longitudinally through an opening in the eraser performs the function of preventing tilting movements of the base of the eraser within the socket and causes the portions of the eraser adjacent to the reinforcing member to bind upon the reinforcing member when subjected to such tilting movements, thereby preventing the withdrawal of the eraser from its socket when subjected to heavy pressures when used for erasing purposes.

An additional advantage attained by my improved structure is that on account of the use 50 of a relatively soft eraser with a central opening, a new eraser may be readily, quickly and easily inserted in the holder by simply compressing the end of the eraser and forcing it into the holder past the lugs 26, as shown in Figure 7, and then after the reinforcing member is placed in the tubular opening of the eraser, this end of the eraser will be firmly held in its socket.

55 When the eraser has been worn down to a point near the sleeve at its lower end, then the sleeve

and nut may be withdrawn and a new eraser substituted.

By having the adjusting screw contained within the eraser a considerable saving in the total length of the combined pencil and eraser is effected, and by having the adjusting screw located wholly within the eraser, the customary round form of the eraser holder and pencil may be maintained without any increase in the diameter, yet permitting the use of an eraser of relatively 10 large diameter.

I claim as my invention:

1. In a device of the class described, the combination of a body, a screw fixed therein, a tubular eraser holder rotatably connected with the body, 15 an eraser within the holder freely movable longitudinally thereof and having an opening through which said screw is extended, a nut connected to the eraser and having said screw extended through it, and means for preventing rotary 20 movement of the eraser when the said body is rotated relative to the eraser holder.

2. In a device of the class described, the combination of a pencil body, a screw support fixed to the body, a screw centrally fixed to the support, 25 an eraser holder, a nut fixed to the eraser holder, a ring fixed to the eraser holder and rotatably connected to the screw support, a screw threaded collar for detachably holding said ring in place, a nut through which said screw is extended, said 30 nut being freely movable longitudinally within the eraser holder, means for preventing the nut from rotating relative to the holder, and an eraser detachably fixed to the nut and formed with a central opening through which said screw 35 is projected, for the purposes stated.

3. The combination of a tubular body, an eraser mounted within the body for longitudinal movement therein, said eraser being formed with a longitudinal opening, a guiding and binding rod 40 supported within said casing extended through and loosely fitted within the opening in the eraser to a point adjacent the outer end of the body portion, and means for moving the eraser longitudinally within the body portion to project one end 45 thereof beyond the body portion and beyond said rod.

4. An improved article of manufacture, an eraser body portion formed of erasing material and having a longitudinal opening shaped to 50 slidly receive a guiding and binding rod, the exterior of the eraser body being formed with a relatively flat side to co-operate with a hollow handle body having a corresponding relatively flat surface on its interior to prevent rotation of 55 the eraser within a handle body portion during longitudinal movement of the eraser within a handle body.

CHARLES A. WATROUS.
